KEY RING

Karl C. Augenstein, Cranston, R. I., assignor to
Speidel Corporation, Providence, R. I., a cor-
poration of Rhode Island

Application January 24, 1940, Serial No. 315,322

9 Claims. (Cl. 70—459)

This invention relates to an improved key ring and method of making the same, and more particularly to a key ring comprising a unitary ring element having its free ends in juxtaposed relation and a keeper therefor having sufficient contact with the ring longitudinally of its extent to adapt it for use with a ring of circular cross-section without liability of rotation about the axis of the ring.

One object of the invention is the provision of a key ring of the character described comprising a ring element and keeper therefor provided with novel means for locking the keeper in position to serve as a closure for the ring and at the same time having ring engaging bearings of such extent as to maintain the keeper at all times substantially within the plane of the ring.

Another object of the invention is the provision of a novel form of keeper as well as improved releasable means for retaining the keeper in position to serve as a closure for the ring element.

Other objects and advantages of the invention relate to various improved details of construction and novel arrangements of the parts, as well as improved methods for forming and assembling the same as will be more fully set forth in the detailed description to follow.

Referring to the drawing:

Fig. 1 is a front elevational view of one form of the structure, showing the keeper in position to serve as a closure for the opening in the ring.

Fig. 2 is a front elevational view of a portion of the key ring structure, showing the keeper in section to illustrate more clearly the arrangement of its parts.

Fig. 3 is a plan view of a stamping which may be formed from thin metal and which is adapted for use in shaping the main body portion or housing of the keeper member.

Fig. 4 is a perspective view of the stamping shown in Fig. 3 after the same has been partially shaped by suitable dies or other means into a form approaching that of the complete keeper housing.

Fig. 5 is an enlarged transverse sectional view through a portion of the keeper and ring member, taken substantially along the line 5—5 of Fig. 1.

Fig. 6 is a perspective view of the spring member,

Fig. 7 is a front elevational view of a somewhat modified form of key ring, and,

Fig. 8 is a front elevational view of a portion of the structure shown in Fig. 6, showing in longitudinal section a portion of the keeper mem-

ber shell or housing and illustrating the position therein of the locking means for releasably retaining the keeper member in position on the ring.

In the embodiment of the invention illustrated in Figs. 1 to 6 of the drawing, 1 designates a ring element which may be formed conveniently from round stock bent to provide a uniform curvature throughout a portion at least of its extent, and having the free ends 2 separated slightly from each other to provide an opening 3 therebetween for receiving a releasable locking member adapted to retain the keeper in position to bridge the opening 3 and maintain the ends 2 against transverse displacement relative to each other.

That portion of the ring element having of necessity a uniform curvature comprises the parts immediately adjacent to the free ends 2, and is of sufficient extent, at least, to provide space for moving the keeper member into position to bridge the opening 3 or into position away from the opening 3 sufficiently to permit transverse displacement of the free ends 2 for removing keys from or placing keys on the ring element.

The keeper member 5 may comprise a housing 6, which may be formed from a plane metal stamping 7, which is shaped in any suitable manner to provide substantially duplicate opposed sides 8 having mating loop portions 9 and a base 10 from which the sides extend.

The base 10 is preferably provided with upturned ends 12, each shaped to fit against the outer curvature of the ring element, and one of the sides 8 may have wings 14 extended outwardly therefrom and adapted to be pressed or spun downwardly against portions of the opposite side 8 to hold the sides in interfitting relation with each other. A leaf spring member 15, which may be provided with or comprise a base 16 and a return bent portion 17 provided with an outwardly extending locking portion 18 having a transversely extending detent 20, is seated upon the base 10 of the casing in such a manner that the ends of the base 16 rest upon the base 10 of the housing at points adjacent to the opposite ends thereof whereby the intermediate arced portion of the spring base may be effective for resiliently moving the locking portion 18 into the opening 3 separating the free ends of the ring element.

The transversely extending detent 20 may project outwardly through a slot 22 formed in one of the sides 8, whereby the upright locking portion 18 of the spring 15 may be moved out of

engaging relation with the ends of the ring element when desired. The upturned ends 12 of the base 10 serve as stops to retain the base 16 of the spring 15 in fixed position relative to the housing 6 at all times, and the opposite side faces of the housing together with the detent 20 projecting through the slot 22 serve to retain the spring member in operative position and to guide the upright portion 18 in its movement into and out of engaging relation with the ends of the ring element.

In forming the keeper member housing, a plane shape 7 may be struck or stamped from any metal sheet of a suitable character. The shape 7 may then be subjected to any further desired stamping or shaping operation to give the same a suitable configuration, which may be substantially as that shown in Fig. 4 of the drawing. Such further stamping or shaping of the plane shape 7 preferably applies lines 23 serving to define the base portion 10 with respect to the sides 8, and impresses each side with a curved depression 24 for receiving the curved portion of the ring element. This further stamping or shaping operation also forms lines of bend 25 for the wings 14 whereby they are capable of being bent readily over the adjacent edges of the mating sides 8 when the sides are pressed together. At the same time, the ends 12 of the base 10 are turned upwardly from the plane of the base into position to fit closely against the ring element when the same is inserted within the keeper.

The formation of the lines of bend indicated at 23 and 25, may, of course, be formed in the shape or blank shown in Fig. 3 as incidental to the stamping out of the same and while all parts thereof are in substantially a single horizontal plane.

The spring member 15 may be in the form 40 of a flat spring having a base 16, which in the form shown is adapted to seat upon the base 10 of the keeper housing, and which has one end return bent to a point adjacent to the longitudinal center of the base and outwardly therefrom to 45 form the locking portion 18 adapted to project within the ring channel and engage the free ends of the ring element. In this form of spring member shown herein the base 16 is longitudinally curved or arc-shaped throughout a substantial portion of its extent thereby providing additional resiliency for supporting the outwardly projecting portion 18. The detent 20 carried by a part 50 of the return bent portion of the spring member projects outwardly transversely thereof, as shown more particularly in Fig. 6 of the drawing, and 55 through the guide slot 22 to a point outwardly of the housing where it is engageable to move the locking portion 18 against the pressure exerted by the base and other portions of the spring.

60 After shaping the keeper housing as above described, the spring member 15 is positioned therein with the detent 20 projecting through the slot 22, and the base 16 thereof in position to rest upon and contact with the base 10 of the housing when the sides 8 are turned upwardly into opposed relation with each other. The sides 8 may 65 then be turned upwardly from the base 10 and pressed into interfitting engagement with each other. Whereupon, the wings 14 are spun or pressed downwardly to engage over corresponding portions of the opposite side 8 and hold the opposite sides of the housing member firmly secured to each other.

70 The ring member 1 may be inserted within the housing prior to the turning of the sides 8 into

interfitting relation with each other, or the ring element may be inserted after completion of the keeper member by first displacing the ends 2 transversely from each other and then threading one of the ends 2 through the grooved recess 5 formed in the housing for receiving the ring element. In either case, after pressing together the opposite sides 8, the wing portions 14 are pressed into close engagement with the opposite side to hold the sides firmly in interfitted position and 10 form a housing for the spring member.

In that form of the invention shown in Figs. 7 and 8, the ring element 1 is similar in all respects to that above described and is similarly provided with free ends 2, separated from each other by a narrow opening 3. The keeper member 30 comprises a housing 31 which may be formed from a metal stamping and shaped after a manner similar to that previously described to provide oppositely positioned mating sides 32 each having depressed areas formed therein to receive a spring member 33, together with portions forming seats 34 for supporting the opposite ends of the base 35 of the spring 33 having an outwardly extending portion 37 adapted to project into the opening 3 25 between the free ends 2 of the ring element. In a manner similar to that previously described, the upright portion 37 is provided with a transversely extending detent 39 adapted to project through a guide opening 40 formed in one of the sides 32 30 whereby it may be actuated to move that portion of the upright 37 out of engaging relation with the free ends of the ring element. The opposite side portions 32 may each be provided with in-turned edges 42 adapted to interfit with each other to provide a spring receiving recess, and one of the sides 32 is provided with wings 43 adapted to be inturned against the outer face of the opposite side 32 after they have been turned into interfitting relation to clamp the sides firmly 40 together. The sides 32 may also be provided with mating loop portions 44 adapted to interfit and form means whereby the structure may be supported from any desired carrier, such as a chain or the like.

45 In each form of the invention the ring element may consist of or comprise a continuous member having its ends arranged in spaced opposed relation with each other. The key supporting portion of the ring element generally may be curved 50 throughout in a uniform or non-uniform manner or may be of a polygonal or irregular shape, it being necessary only that the portions thereof adjacent the free ends be so curved as to permit relatively free sliding movement of the keeper member thereon from a position bridging the free ends into a position entirely upon one of the free ends and outwardly from the opening 3 to such an extent as to permit transverse displacement of the free ends 2 for placing keys thereon or removing keys from the ring element, as well as to permit removal of the keeper member from the ring element or its replacement thereon when desired.

55 It will be noted that in the present construction the keeper member is in each case provided with oppositely positioned grooves or other means forming a continuous channel fitting closely about and slidably securing the uniformly curved portions of the ring element, and the width of the keeper member is such as to provide a ring channel of substantial longitudinal extent therein whereby the ring element may be formed from round stock and at the same time be retained within the keeper, by reason of the curvature 70 75

of the channel, so as to prevent rotation of the keeper axially of the ring element.

The construction and arrangement of the parts in each of the forms shown is such as to retain the novel spring locking member in position to prevent its displacement, and at the same time provide a novel form of locking means for a device of this character which comprises a leaf spring structure of a character capable of extended use without fatigue, since the springs action is confined substantially to a relatively long arc-shaped base and the degree of distortion of which is relatively slight for moving the upright locking portion within the limits defined by the path of travel of the transversely extending detent member within its guide slot.

What I claim is:

1. In a key ring, the combination with a continuous ring element in the form of a loop having free ends located in spaced opposed relation with each other and portions adjacent the free ends uniformly curved, a keeper member comprising a housing having oppositely positioned interfitting sides each provided with curved grooves registering with each other in the assembled positions of the opposed sides to form a single continuous recess curved to slidably receive the uniformly curved portions of the ring element, a spring member positioned within the housing having oppositely positioned end portions and an angularly related portion located between said end portions and movable to engage releasably the free ends of said ring element, and means carried by the housing supporting said oppositely positioned ends in substantially fixed positions relative to the path of travel of said ring element.

2. In a key ring, the combination with a continuous ring element in the form of a loop having free ends located in spaced opposed relation with each other and portions adjacent the free ends uniformly curved, a keeper member comprising a housing having oppositely positioned interfitting sides each provided with curved grooves registering with each other in the assembled positions of the opposed sides to form a single continuous recess curved to slidably receive the uniformly curved portions of the ring element, means carried by said sides for supporting the base portion of a spring member in substantially fixed position relative to said opposed sides, and a flat spring member comprising a base carried by said supporting means and an upright portion supported by said base and movable into position to engage releasably the free ends of said ring element and retain the keeper member in fixed position relative to the ring element.

3. A key ring comprising a continuous ring element having free ends located in spaced opposed relation with each other and portions thereof adjacent to the free ends curved uniformly, a keeper member comprising opposed sides having mating grooves therein to form a bearing slidably receiving the uniformly curved portions of the ring elements whereby the keeper may be moved into position to bridge the opening between the free ends of said ring element, a spring member having an elongated leaf portion supported by said keeper member and a portion extending outwardly therefrom for movement into and out of the opening separating the free ends of said ring element, and a detent carried by the outwardly extending portion and engageable from outwardly of said keeper member to move the outwardly extending portion of said

spring member out of the opening between the free ends of the ring element against the tension exerted by said spring.

4. A key ring comprising a continuous ring element having free end portions located in spaced opposed relation with each other and having portions thereof adjacent to the free ends uniformly curved, a keeper member comprising a housing provided with a curved channel slidably receiving the curved portions of the ring element adjacent to the free ends thereof, a flat spring member carried by said housing and having a portion extending outwardly therefrom to project within the said channel, and detent means carried by the outwardly extending portion of said spring member projecting through a portion of the housing and actuatable for moving said outwardly extending portion out of the channel against the tension exerted by the spring.

5. A key ring comprising a continuous ring element having free end portions located in spaced opposed relation with each other and having portions thereof adjacent to the free ends uniformly curved, a keeper member comprising opposite sides and a base portion connecting said sides, a flat spring member having an elongated portion carried by said base and a portion projecting outwardly intermediate the length of said elongated portion and movable into position between the free ends of said ring element or out of position therebetween.

6. In a device of the character described, a keeper member comprising a housing having spaced opposed sides shaped to provide a member receiving recess extending within the housing and having a wall portion connecting said sides, a holding member carried by said housing having an elongated resilient portion and a return bent portion extending outwardly laterally from the elongated portion of the member and movable into and out of the member receiving recess, means carried by said housing supporting said holding member at points adjacent to the ends of the longitudinally extending resilient portion to permit flexing of the resilient portion intermediate its ends, and a detent carried by the laterally extending return bent portion of the holding member extending outwardly of the housing and engageable for moving the laterally off-set portion of the holding member inwardly toward the resilient portion thereof.

7. In a device of the character described, a keeper member comprising a housing having a member receiving recess formed therein, a holding member carried by the housing and having a longitudinally extending resilient portion, means carried by the housing supporting the opposite ends of the longitudinally extending resilient portion of said holding member in such a manner as to permit flexing of the intermediate resilient portion thereof, and means carried by said holding member and located intermediate the ends of the resilient portion movable into the member receiving recess through flexing action of the resilient portion of said holding member.

8. In a device of the character described, a keeper member comprising a housing having a member receiving recess formed therein, a holding member carried by the housing and having a longitudinally extending resilient portion provided with free end portions, means forming a portion of the housing supporting the free end portions of said holding member while permitting flexing of the intermediate resilient portion

thereof in a direction transversely of its longitudinal extent, a member carried by said holding member and located intermediate the ends of the resilient portion thereof of movable into the member receiving recess through action of the resilient portion of the holding member, and detent means carried by said movable recess entering member having a portion extending outwardly of the housing operable to move the recess entering member out of the recess against the action of the resilient portion of the holding member.

9. In a device of the character described, a keeper member comprising a housing shaped to provide a member receiving recess extending within the housing from one side thereof, a hold-

ing member having an intermediate resilient portion provided with free ends and a portion located between the free ends and angularly positioned relative to the resilient portion movable under the influence of the resilient portion into the member receiving recess of the housing, means carried by said housing supporting the free ends of said holding member each in substantially fixed relation to the recess, and a detent carried by the movable portion of said holding member having a part thereof extending outwardly of the housing and engageable for moving the movable portion of the keeper member out of the recess in said housing.
